US00D400494S

United States Patent

[19]

Blase

[11] Patent Number: Des. 400,494

[45] Date of Patent: **Nov. 3, 1998

[54] RECHARGEABLE BATTERY

[75] Inventor: **Dan Blase**, Everett, Wash.[73] Assignee: **Intermec Corporation**, Everett, Wash.

[**] Term: 14 Years

[21] Appl. No.: 59,622

[22] Filed: Sep. 13, 1996

[51] LOC (6) Cl. 13-02

[52] U.S. Cl. D13/103

[58] Field of Search D13/103, 118, D13/119; 429/96-100, 163, 176

CLAIM

The ornamental design for a rechargeable battery, as shown and described.

DESCRIPTION

FIG. 1 is a top front isometric view of a rechargeable battery showing my new design;

FIG. 2 is a bottom rear isometric view thereof;

FIG. 3 is a top plan view thereof;

FIG. 4 is a bottom plan view thereof;

FIG. 5 is a right side elevational view thereof;

FIG. 6 is a left side elevational view thereof;

FIG. 7 is a front elevational view thereof; and,

FIG. 8 is a rear elevational view thereof.
